[57] CLAIM

The ornamental design for combined bellows and fireplace poker, as shown and described.

DESCRIPTION

FIG. 1 is a front perspective view of a combined bellows and fireplace poker showing my new design;
FIG. 2 is an enlarged fragmentary view wherein portions thereof have been omitted for convenience of illustration;

FIG. 3 is a view taken from the side opposite FIG. 2 wherein portions thereof have been omitted for convenience of illustration;

FIG. 4 is a bottom plan view;

FIG. 5 is a perspective view showing a second embodiment of my design;

FIG. 6 is an enlarged fragmentary view of a second embodiment of my design wherein portions thereof have been omitted for convenience of illustration;

FIG. 7 is a view taken from the side opposite FIG. 6 wherein portions thereof have been omitted for convenience of illustration;

FIG. 8 is a bottom plan view of the FIG. 5 embodiment;
FIG. 9 is a perspective view showing a third embodiment of my design;

FIG. 10 is an enlarged fragmentary view of a third embodiment of my design wherein portions thereof have been omitted for convenience of illustration;

FIG. 11 is a view taken from the side opposite FIG. 10 wherein portions thereof have been omitted for convenience of illustration; and,

FIG. 12 is a bottom plan view of the FIG. 9 embodiment of my design.
